UNITED STATES PATENT OFFICE.

LEO M. LAROSE, OF DETROIT, MICHIGAN, ASSIGNOR TO ISREAL WEINSTEIN, OF CHICAGO, ILLINOIS.

SIGNAL LAMP FOR VEHICLES.

Application filed October 5, 1923. Serial No. 666,714.

To all whom it may concern:

Be it known that I, LEO M. LAROSE, a citizen of the Dominion of Canada, residing at Detroit, in the county of Wayne and State 5 of Michigan, have invented a new and useful Signal Lamp for Vehicles, of which the following is a specification.

This invention relates to signal devices for vehicles, and more particularly to devices for use upon taxicabs and the like for indicating whether or not the vehicle is available for hire.

It is the object of the invention to provide a signal device having the nature of a sign, 15 preferably illuminated, and adjustable from a substantially vertical position, in which it may be easily read, to a substantially horizontal position preventing reading of the sign.

20 The invention consists also in a provision for expediting assembly of the sign and for facilitating its installation in a vehicle.

A preferred embodiment of the invention is hereinafter described and is illustrated in 25 the accompanying drawing, in which,

Fig. 1 is a view in side elevation of the sign installed upon a vehicle and in its position of adjustment indicating availability of the vehicle for hire.

30 Fig. 2 is a vertical sectional view of the same, taken upon line 2—2 of Fig. 1.

Fig. 3 is an end view of the signal, adjusted to its stored or non-indicating position.

35 Fig. 4 is a detail sectional view, taken on line 4—4 of Fig. 1, showing one of the pivotal connections between the signal and its supporting hangers.

In these views the reference character 1 40 designates a rectangular casing formed preferably of sheet-metal and having opposed elongated openings 2 in its side walls, in which openings are fitted glass plates 3. 4 designates a sign which is inscribed upon 45 each of said plates in any suitable manner adapted to be illuminated by light originating within the casing and passing through the plates, said sign having any such wording as will indicate availability of the vehicle to passengers. A source of light is 50 arranged within the casing to illuminate the sign 4, said source ordinarily being an electric bulb 5 engaging a suitable socket 6. It is preferred to mount said socket in one of 55 the side walls of the casing, midway be-

tween the ends of the casing and above the level of the openings 2. Below the bulb 5 provision is made for reflecting the light rays emanating therefrom through both of the openings 2. Thus, as seen in Fig. 2, a sheet metal plate 7 is folded to a V-form and is arranged with its apex uppermost in the lower portion of the casing. The lower edges of said plate are formed with oppositely projecting flanges 7' which are rigidly connected by solder or other means to the bottom 8 of the casing. The longitudinal edges of the bottom piece 8 are upturned as indicated at 9 to retain the glass plates 3, and flanges 10 upon the end members of the casing exercise a similar function. 11 designates flanges formed upon the side walls of the casing along the upper edges of the openings 2 forming seats and a backing for the plates 3, as best seen in Fig. 2. The double reflector member 7 and the bottom piece 8, to which said member is rigidly secured, form an assembly unit which is attached to the remaining portion of the casing 1 by a pair of bolts 12, the heads 13 of which are engaged in the bend of the member 7, said bolts projecting up through the respective end portions of the casing and being engaged above the casing by suitable clamping nuts 14. Said bolts and nuts are employed also to secure to the top of the casing 1 a sheet metal strap 15, the ends 15' of which are upturned and pivotally connected by pins 16 to a pair of hangers 17. The latter are attached to such a portion 18 of the vehicle as will allow either the driver or conductor of the vehicle to readily reach the device, and which will further permit the sign to be readily read by prospective patrons of the vehicle. With the pivot pins 16, there are associated means for holding the casing yieldably either in the vertical position of use shown in Figs. 1 and 2, or in the horizontal stored position shown in Fig. 3. Thus each hanger is formed with ribs 19 diametrical to the corresponding pin 16, and the upstanding strap ends 15' are formed with corresponding transverse indentations 20 also radial to the pins 16. A spring 21 is coiled upon each of said pins and exerts pressure upon the corresponding end 15' to hold the same firmly against the corresponding hanger 17. When the casing 2 is vertical, a rib 19 of each hanger engages in an indentation 20 of the corresponding 100 105 110 115

member 15', and in the horizontal or stored position of the casing the relatively transverse ribs 19 and grooves 20 are in engagement. In either of said positions, the 5 springs 21 resist disengagement of the ribs 19 and grooves 20 and consequently tend to maintain the casing 1 in whichever limiting position it may occupy.

From the preceding description it will be 10 evident that the invention provides a signal device which is well adapted for both day and night use, and which, by its position of adjustment, will indicate clearly to the public whether or not the vehicle is available to 15 passengers.

What I claim is:

1. In a signal device, a casing, a source of light in the upper portion of said casing, and a V-shaped double reflector within said 20 casing below said source of light, the walls of said reflector converging upwardly toward said light source and being rigidly secured to the casing bottom at their diverged edges, and a headed member securing 25 said reflector to the top of the casing, the head of said member being engaged within the angle formed by the convergent walls of the reflector.

2. In a signal device, a casing, a source

of light within said casing, signs carried by 30 the casing at opposite sides of said source of light, a reflector member secured in a unitary relation to the casing bottom, a support for the casing exteriorly engaging the top thereof, and a member extending 35 through the casing top, engaging said reflector member and said support, securing said member and support in place and acting through said reflector member to hold the casing bottom in position. 40

3. In a signal device, a casing, a source of light within said casing, signs carried by 45 the casing at opposite sides of the source of light, a reflector member secured to a wall of said casing and projecting between said signs, a support for said casing, exteriorly engaging a wall of the casing opposite to that from which said reflector member projects, and a clamping connection between said reflector member and said support retaining the same in their positions of assembly and acting through said reflector member to hold in its assembly position the wall from which said member projects. 50

In testimony whereof I sign this specifica- 55
tion.

LEO M. LAROSE.
